UNITED STATES PATENT OFFICE

JAMES BRUCE McDANIEL, OF MACON, GEORGIA

WATCH-CRYSTAL-FITTING DEVICE

Application filed July 24, 1928. Serial No. 295,066.

This invention appertains to improvements in watch crystal fitting devices, and has for its principal object to provide an extremely simplified but durable and efficient means, 5 whereby the pattern of a desired shape and size of crystal may be readily and accurately traced on a crystal blank directly from the inside edge of the bezel of the watch case to which the completely finished crystal is to be 10 applied.

Another object of the invention is to provide a device of the class set forth and as hereinbefore characterized, which is in the nature of a base to receive thereon the blank 15 from which a crystal is to be formed, and which has a clamping means mounted on the same to sustain the watch case firmly in position on the blank while the operator traces the outline of the inner edge of the bezel onto 20 the blank by means of a hand implement or tool.

With the foregoing and other equally important objects in view, the invention resides in the certain new and useful combination, 25 construction and arrangement of parts as will be hereinafter more fully described, set forth in the appended claims, and illustrated in the accompanying drawing, in which:

Figure 1 is a perspective view of a practical 30 embodiment of the invention as it appears when in position of use,

Figure 2 is a vertical longitudinal section thereof, and

Figure 3 is a vertical transverse section 35 taken on the line 3—3 of Figure 2.

Referring to the drawing, wherein like characters of reference designate corresponding parts throughout the several views thereof, the embodiment of the device, as shown 40 therein by way of example, comprises a base 10, which is preferably formed of a wooden block or the like having a depression 11 formed centrally of its upper face, and of a depth to seat a crystal blank *a* within the 45 same, and in a manner that the upper face of the blank will lie flush in the plane of the upper face of the base. The depression 11 is preferably formed in a centrally raised portion 12 at the upper side of the base. 50 Rising from the opposite ends of the base

10 are flanges 13, which extend parallel to the opposed ends of the raised portion 12 and to form depressions 14 therebetween, the top edges of these flanges being disposed substantially in the plane of the top face of the 55 raised portion 12.

Pivoted, as at 15, at the opposite sides of the base 10 and extending transversely of the upper side thereof are a pair of curved clamping frames or supports 16 in the center of each of which a vertically adjustable clamping member 17 is supported. These clamping members 17 are preferably in the form of screw-threaded rods, having winged finger grips 18 at their upper ends, and swivelled 60 foot pieces 19 at their lower ends.

In the use of the device, after a crystal blank *a* has been positioned in the depression 11, at the center of the raised portion 12 of the base 10, a watch case *b* will thereafter be centered on the blank *a* in opened position, and with the front side of the bezel thereof resting directly on the latter. A pair of clamping members or bars 20 will now be laid lengthwise on the base 10 in inwardly inclined and aligned relation, and with their outer ends abutted against the inner sides of the end flanges 13, and their inner ends overlying the opposite sides of the raised portion 12 and the horizontal portion of the watch case *b*. 70

These clamping members or bars 20 will be laid in the plane of the longitudinal center of the base 10, so as to underlie the foot pieces 19 of the clamping members or screws 17, and they are supported in the desired inclined 75 position by being rested against the opposite ends of the centrally raised portion 12 of the base 10. When properly positioned, as indicated, the clamping members or screws 17 will be turned to tighten the foot pieces 19 thereof downwardly against the upper side of the clamping members or bars 20.

As shown in Figure 2, the inner end of the clamp members or bars 20 will preferably have grooves or depressions 21 formed transversely of their lower faces to engage over the adjacent portions of the watch case *b*, so that, when the clamp members or screws 17 are tightened downwardly against the clamp members or bars 20, the watch case *b* will be 80 85 90 95 100

securely and firmly clamped against the crystal blank *a*.

When the watch case *b* is finally clamped in position, the operator will trace the outline of the inner edges of the bezel onto the underlying crystal blank *a* by means of a finely pointed implement or tool (not shown). When the tracing of the required shape and size of the proposed crystal on the blank *a* is completed, the clamp members or screws 17 will be loosened up from the clamp members or bars 20 and the latter, together with the watch case *b*, then removed from the base 10. The blank *a* can now be displaced from the depression 11 by swinging the clamp frames or supports outwardly toward the opposite ends of the base 10. After the removal of the blank *a* from the depression 11, the outer portions of the same, surrounding the tracing thereon, will be easily broken away by the use of pliers or the like, when the raw edges of the usable portion of the blank may then be smoothed down in any suitable manner to finally finish the crystal 25 for engagement with the bezel of the watch case *b*.

It is to be noted that the invention contemplates the use of crystal blanks of but one size, so that all of the same may be snugly 30 fitted into the depression 11 arranged for their reception in the upper side of the raised portion 12 of the base 10.

Without further description, it is thought that the features and advantages of the invention will be readily apparent to those skilled in the art, and it will of course be understood that changes in the form, proportion and minor details of construction may be resorted to, without departing from the 40 spirit of the invention or its scope as claimed.

Having thus fully described the invention, what is claimed is:

1. A watch crystal fitter comprising a base, a flat centrally disposed portion rising from said base and having a seat therein to receive a sheet of material from which a crystal is to be cut, shoulders formed at the opposite ends of said raised portion, flanges rising from the opposite ends of said base, clamp 45 bars adapted to be laid on the opposite end portions of said base crosswise of said shoulders and with their outer ends abutted against said flanges and the inner end portions thereof resting on adjacent edges of a template which is adapted to be placed on the material in said seat, arched members disposed transversely of and above said base, and clamp 50 members carried by said arched members and adapted to engage said clamp bars at points 55 thereon in line with said shoulders.

2. A watch crystal fitter comprising an elongated base, a flat portion rising centrally from the upper side of said base and having a seat therein to receive a sheet of material 60 from which a crystal is to be cut, inclined

shoulders formed at the opposite ends of said raised portion, flanges rising from the opposite ends of said base in opposed relation to said shoulders, clamp bars adapted to be laid on the opposite end portions of said base crosswise of said shoulders and with their outer ends abutted against said flanges and the inner end portions thereof resting on the adjacent sides of a template which is adapted to be placed on the material in said seat, arched members disposed transversely of and above said base, pivot connections for said arched members to admit of the latter being swung outwardly from operative vertical positions at the opposite sides of said raised portion, and clamp members carried by said arched members and adapted to engage said clamp bars when disposed in their vertical 70 positions.

Signed at Macon in the county of Bibb and State of Georgia this 16 day of July, A. D. 85 1928.

JAMES BRUCE McDANIEL.
